UNITED STATES PATENT OFFICE.

EARNEST W. LADD, OF NEW YORK, N. Y., ASSIGNOR TO ELEANOR V. GEORGE, OF NEW YORK, N. Y.

RECORD-FILING RACK.

1,417,471.

Specification of Letters Patent. Patented May 23, 1922.

Application filed April 4, 1921. Serial No. 458,430.

To all whom it may concern:

Be it known that I, EARNEST W. LADD, a citizen of the United States, residing in the borough of Manhattan, city, county, and 5 State of New York, have invented a certain new and useful Improvement in Record-Filing Racks, of which the following is a specification, reference being had to the accompanying drawings, which form a part of 10 the same.

An object of my invention is to provide a rack for filing phonograph records of the disc type in larger numbers in a given space than has heretofore been practiced.

15 Another object of my invention is to make such a rack in a unitary form so that it may be utilized in connection with standard forms of phonograph cabinets.

Other objects of the invention will be apparent upon a reading of this specification in connection with the accompanying drawings in which—

Fig. 1 is a perspective view of a phonograph cabinet containing my rack, and

25 Fig. 2 is a diagrammatic view of the arrangement of the partitions of the rack; this figure shows an axial broken line with the arrangement of the partitions and stops on one side thereof and arrangement of a few 30 partitions on the other side thereof; it will be understood that the arrangement of both sides of this axial line is the same as shown in the lower part of said figure.

As will be observed from a perusal of 35 Fig. 1 of the drawings my record rack unit is adapted to fit in the record compartment of a phonograph cabinet. Normally the rack is contained entirely within the record compartment of the cabinet and the cabinet 40 doors are closed. When it is desired to use records contained in the rack between partitions thereof whose outward radii are obstructed by the cabinet structure, the rack is drawn out of its compartment and the record 45 readily selected. In practice this rack is mounted on extensible ways which have a slidable connection with the cabinet and which are also provided with stops to limit the degree of withdrawal of the rack from 50 the cabinet, which sliding construction permits the withdrawal of the rack from the cabinet sufficiently to enable the ready use of all of the record filing spaces in the rack.

I have not shown or described any special 55 construction for suspending or supporting

the rack and permitting and limiting the degree of its withdrawal from the cabinet for the reason that such constructions are common, especially in business filing cabinets.

Referring now in detail to the drawings 3 60 is a phonograph cabinet, having the doors 4, 4 to the record chamber 5, within the record chamber is a record filing rack or drawer. This rack is provided with a base 6 and a top 7, between which is mounted a plurality 65 of partitions 8. These partitions preferably extend only a relatively short distance toward the inside of the rack and spaces 9 are formed between the same and their adjacent partitions. I have provided stops 10, 70 11 and 12 which are mounted in the base of the rack and extend to a sufficient height to effectively stop records which are filed in the spaces 9. The dotted lines in Fig. 2, between the stops and the partitions, are 75 imaginary and as a matter of practice the space between the inner ends of the partitions 8 and the stops is unbroken. These dotted lines are shown merely for the purpose of illustrating substantially the limits 80 of the lateral travel of records inserted in the spaces 9.

The radial arrangement of the partitions 8 is such that while several of said partitions may be parallel to each other, a substantial 85 number, and preferably nearly all of such partitions are out of parallel with each other; furthermore, the arrangement of partitions is such as to utilize for record filing purposes the least amount of space compared 90 with the number of records filed. It will be observed from the special arrangement of the stops 10, 11 and 12 that records of varying sizes may be conveniently filed in this rack in view of the varying difference of distance between the portion of said stops in alignment with the spaces between the particular partitions. These stops 10, 11 and 12 are arranged angularly to an imaginary 95 line drawn from the middle of the front of 100 the rack to the middle of the back thereof.

I have shown what I believe to be the best embodiment of my invention. I do not, however, wish to be limited to the form of disclosure made, but what I desire to cover 105 by Letters Patent is set forth in the appended claims.

Claims:

1. In a rack for phonograph records of the disc type, a base, a top, partitions ex- 110

tending inwardly along said base and top a relatively short distance so as to provide an open uninterrupted space beyond the inner edges of said partitions permitting intimate association of the inner edges of records filed adjacent to each other, substantially all of said partitions being arranged out of parallel with each other and extending inwardly from the sides and front of said rack.

2. In a rack for phonograph records of the disc type, a base, a top, partitions extending inwardly along said base and top a

relatively short distance so as to provide an open uninterrupted space beyond the inner edges of said partitions permitting intimate association of the inner edges of records filed adjacent to each other, substantially all of said partitions being arranged out of parallel with each other and extending inwardly from the sides and front of said rack, and stops angularly arranged along and with respect to the middle portion of said rack taking the line thereof from the center of the back to the center of the front of said rack. 25

EARNEST W. LADD.
